Thomas H. Ward, John E. Roberts & Henry S. Hubbell, of Utica, New York,
Letters Patent, No. 1160. Dated Oct. 25. 1859.

The schedule referred to in these Letters Patent and making part of the same —

In all which it may concern:

Be it known that we, Thomas H. Ward, John E. Roberts, of the City of Utica, County of Oneida, and State of New York, and Henry S. Hubbell of the City of Buffalo, County of Erie and State of New York, have invented or produced a new and original design for a Cooking Stove called the "Mountain" and we do, therefore, declare that the following is a full and exact description of the same, reference being had to the accompanying drawings and the letters of reference marked thereon.

Letter A, the top plate. B, one of the oven sides, both being the same. C, one of the oven doors, both being the same. D, D, the front of the Stove. E, E, the front doors. F, the end or fire door attached to the side I, of Stove. G, the front bottom or fire Bed Hearth, with the Slide Hearth. H, the oven Top.

What we claim as our invention or production and desire to secure by Letters Patent is the general design and configuration represented in the accompanying photograph.
